CLAIM

The ornamental design for a hand-held device housing, as shown and described.

DESCRIPTION

FIG. 1 is a front perspective view of a hand-held device housing showing our new design;

FIG. 2 is a rear perspective view thereof;

FIG. 3 is a front elevational view thereof;

FIG. 4 is a side elevational view thereof;

FIG. 5 is another side elevational view thereof;

FIG. 6 is an end view thereof;

FIG. 7 is another end view thereof; and

FIG. 8 is a rear elevational view thereof.

FIG. 9 is a front perspective view of a hand-held device housing showing an alternative embodiment of our design;

FIG. 10 is a rear perspective view thereof;

FIG. 11 is a front elevational view thereof;

FIG. 12 is a side elevational view thereof;

FIG. 13 is another side elevational view thereof;

FIG. 14 is an end view thereof;

FIG. 15 is another end view thereof; and,

FIG. 16 is a rear elevational view thereof.
